UNITED STATES PATENT OFFICE

91,774

DESIGN FOR A TABLE STOVE

Alfred F. Fukal, Chicago, Ill., assignor to Chicago Flexible Shaft Company, Chicago, Ill., a corporation of Illinois

Application January 15, 1934, Serial No. 50,405

Term of patent 7 years

To all whom it may concern:

Be it known that I, ALFRED F. FUKAL, a citizen of the United States, residing at Chicago, in the county of Cook and State of Illinois, have invented a new, original, and ornamental Design for a Table Stove, of which the following is a specification, reference being had to the accompanying drawing, forming part hereof.

In the drawing:

Figure 1 is a top view of a table stove showing my new design;

Fig. 2 is a side elevation thereof, and

Fig. 3 is a partial section thereof.

I claim:

The ornamental design for a table stove substantially as shown.

ALFRED F. FUKAL.
